UNITED STATES PATENT OFFICE.

EDWARD H. BARTON, OF SPRAGUE, WASHINGTON.

RATCHET-TOOL.

1,309,715.

Specification of Letters Patent. Patented July 15, 1919.

Application filed September 26, 1917, Serial No. 193,358. Renewed December 12, 1918. Serial No. 266,496.

To all whom it may concern:

Be it known that I, EDWARD H. BARTON, a citizen of the United States, residing at Sprague, in the county of Lincoln and State 5 of Washington, have invented a new and useful Ratchet-Tool, of which the following is a specification.

The invention relates to a ratchet tool, and more particularly to the class of reversible 10 screwdrivers and drills of the ratchet type with interchangeable bits.

The primary object of the invention is the provision of a tool of this character, wherein bits for the execution of different 15 characters of work, can be interchanged with despatch, each bit being reversible, thus embodying two implements in one.

Another object of the invention is the provision of a tool of this character wherein 20 the construction thereof is novel in form, to assure the easy handling of the tool, and to render the tool positive in operation.

A still further object of the invention is the provision of a tool of this character, 25 which is simple in construction, thoroughly reliable and efficacious in operation, strong, durable, and inexpensive to manufacture.

Other objects will be in part obvious, and in part hereinafter pointed out.

The invention accordingly consists in the 30 features of construction, combination of elements, and arrangement of parts, which will be exemplified in the construction hereinafter set forth, and the scope of the application of which will be indicated in the following claims.

In the accompanying drawing:—

Figure 1 is a vertical longitudinal sectional elevation of a tool, constructed in accordance with the invention, the bit and sleeve being shown by full lines in normal position, and by dotted lines in another position for the adjustment of said bit.

Fig. 2 is a transverse sectional view on 45 the line 2—2 of Fig. 1, looking in the direction of the arrow, showing the catch or actuator for the pawl or dog in neutral position.

Fig. 3 is a similar view to Fig. 2, with the catch or actuator moved to the left.

Fig. 4 is a similar view with the catch or actuator moved to the right for the reverse action of the ratchet mechanism.

Fig. 5 is a fragmentary plan view of the stock of the tool.

Fig. 6 is a plan view of the ferrule.

Fig. 7 is a fragmentary side elevation of the sleeve, shank and bit.

Fig. 8 is a perspective view of the catch or actuator.

Fig. 9 is a perspective view of the pawl 60 or dog.

Fig. 10 is a plan view of a screw-driver and drill bit.

Fig. 11 is a plan view of a modified form of bit. 65

Fig. 12 is a sectional view on the line 12—12 of Fig. 7.

Similar reference characters indicate corresponding parts throughout the several views of the drawing. 70

Referring to the drawing in detail, 10 designates a stock, preferably made from metal having formed longitudinally therein, and opening through the outer end thereof, a chamber 11 for accommodating bits, 75 while formed in the opposite end, is the socket 12, which receives the inner end of a rotatable shank 13. The socket 12 is formed with a widened portion 14, for accommodating a ratchet wheel 15 and its hub 16, fixed 80 to or integral with the shank 13, and this hub 16 is shaped to constitute a cone for bearing balls 17, which are held within the portion 14 of the socket 12, thereby minimizing friction in the rotation of the shank. 85 Surrounding the stock 10 for a greater portion of its length, is a sleeve-like hand grip or handle 18, which is fixed thereto in any suitable manner, while telescoped upon the remaining portion of the stock 10, is a 90 ferrule 19, which is formed with a reduced outer end portion 20, of a cross-sectional diameter greater than the cross-sectional diameter of the shank 13, for the snug 95 slideable fitting of a sleeve 21 therein, which sleeve loosely surrounds the shank 13, and is for the purpose hereinafter described.

Tapped through the ferrule 19 and the stock 10, to intersect the socket 12, is a retaining screw 22, which has its inner end engaged in the annular groove 23 formed in the shank 13, and in this manner the latter is swiveled in the stock, while said screw 22 also fastens the ferrule upon the stock. 100

The wall of the portion 14 of the socket 10, is cut away to provide a recess 24, for accommodating a duplex pawl or dog 25, and opening into the recess 24, is a counter-seat 26, which has intersecting the same a notch 27, the latter and the counter- 105

seat being formed in the outer face of the wall; and they accommodate an outwardly-bowed spring 28, which is formed with hook ends 29, one being engageable in the notch 27, and the other engageable with the pawl or dog 25 to hold the same against movement out of the recess 24, and in operative relation to the ratchet wheel 15. The spring 28 is held in place by the ferrule 19, engaged 10 with the stock.

The ferrule 19 is formed with a transverse slot 30, having at intervals in one edge notches 31, and working in this slot is the finger-engaging nib or end 32 of the catch 15 or actuator, which is in the form of a mutilated disk 33, which loosely surrounds the shank 13, the disk being centrally perforated for accommodating the shank. The mutilated portion of said disk 33 serves as a cam 20 edge 34 for action upon the duplex pawl or dog 25, for the right-hand or left-hand ratchet action thereof on the ratchet wheel 15, or for permitting the pawl to assume a neutral position for locking the ratchet 25 wheel against rotation in either direction. The notches 31 permit the nib or end 32, which is suitably roughened for easy finger manipulation, to engage in any one of said notches for holding the catch or actuator in 30 adjusted position.

The shank 13 is formed with a bifurcated outer end, the bifurcation 34^a of which receives therein a reversible and removable bit 35, which is formed with a screw-driver end 36 and opposite drill end 37, thus effecting two tools in one, the bit being formed in one face medially thereof with an indentation 38, for the engagement therein of a pivot screw 39, which is threaded through 40 one limb of the bifurcated end of the shank 13, so that the bit 35 can be reversed for presenting either end thereof in working position.

The bit 35 can be removed for permitting 45 the interchanging of bits, for example, the substitution of the bit 40 shown in Fig. 11 of the drawing, which is formed with different width screw-driver ends 41, thereby making the bit handy for use with different sizes 50 of screws. To remove the bit, it is necessary to slide the sleeve 21 inwardly of the ferrule 19, and thereafter swing the bit at right angles to the shank 13, thereupon on twisting the bit, the bifurcated end of the shank will 55 be caused to spread, and a slight pull upon the bit will disengage it from the screw 39 for the quick removal of said bit. Now to insert a substitute bit, each of the bits is formed in one or both opposite faces with longitudinal channels or grooves 35^a to provide a guide-way for the screw 39, so that 60 on inserting either end of the bit in the bifurcation in the shank 13, the rounded end of the screw 39 will engage in the groove 65 35^a, thereby guiding the bit until the screw

39 reaches the indentation 38, whereupon the bit will be pivotally engaged in the bifurcated end of the shank. Thus in this manner the removal or the loosening of the screw 39 is eliminated when changing the bits, 70 or detaching one of the same from the tool.

Surrounding the shank 13, within the ferrule 19, is a coiled expansion spring 42, which has one end working against the catch or actuator 33, and its opposite end bearing 75 against the inner end of the sleeve 21, which is formed with a seat 43 for this end of the spring, the latter being designed to force the sleeve outwardly of the reduced end 20 of the ferrule 19. The outward movement of 80 said sleeve is limited by contact thereof with the screw 39, in which position said sleeve holds the bit 35 against reverse movement, or swinging in the bifurcated end of the shank. The sleeve at its outer end portion 85 is formed with a knurled external surface 44, to be gripped by the fingers of the user when the tool is in operation, thereby guiding and holding said tool properly centered 90 relative to the work. The shank 13 is freely 95 rotatable in the sleeve, while the sleeve is freely rotatable in the ferrule. The spring 42 by bearing at one end against the sleeve 21 and at the other against the actuator 33, performs two functions. It maintains the 95 sleeve in extended relation and gives tension to the actuator and holds it to its work.

Fitted in the outer end of the chamber 11, in the stock 10, is a removable cap 45, the rim 46 of which is slotted and telescopes into 100 the chamber, and working through the slots is a coiled spring 47, which frictionally engages the wall of the chamber 11, to retain the cap in the stock to close the chamber 11 therein.

It will be obvious, that the tool can be operated in either direction for either right- or left-hand rotation, and when the tool is adapted for use as a screw-driver, it may be used to drive the screw into the work, 110 without changing the grip on the handle, or removing the bit from the screw head, and by shifting the catch or actuator 33, the screw may be withdrawn under like conditions. If the catch or actuator 33 is shifted 115 to neutral position, shown in Fig. 2 of the drawing, the pawl or dog 25, will lock with the ratchet wheel 15, and the shank 13 will not revolve in either direction, and the tool may be used in the usual manner.

On moving the sleeve 21 inwardly within the ferrule 19, the bit 35 can be reversed, so that it may be positioned for use as a drill or screw-driver, accordingly to the end presented to the work. The sleeve 21, when in 125 the position shown in Fig. 1 of the drawing, locks the bit against reversal.

It is obvious that by reason of the bits being detachable, different sizes and combinations of bits can be interchanged, thereby 130

making the tool handy for the execution of different characters of work.

From the foregoing, it is thought that the construction and manner of operation of 5 the tool will be clearly understood, and therefore a more extended explanation has been omitted.

What is claimed is:—

1. In a tool of the character described, a shank having a bifurcated end, a bit mounted in the bifurcated end for swinging movement to permit reversal thereof, a freely rotatable sleeve slidable on the shank for movement over the bifurcated end to hold the bit in its reversed position, means for limiting the longitudinal movement of the sleeve, a stock supporting the shank, a ferrule on said stock surrounding the shank and sleeve, and a spring within the ferrule 15 and acting upon the sleeve to normally hold the same in its extended position, said sleeve being slidable inwardly against the tension of the spring so as to allow the reversal of the bit.
- 25 2. In a tool of the character described, a shank having a bifurcated end, a bit mounted in the bifurcated end for swinging movement to permit reversal thereof, a freely rotatable sleeve slidable on the shank for movement over the bifurcated end to hold the bit in its reversed position, a pivot screw for detachably holding the bit in said bifurcated end and forming a stop for the sleeve, and a spring for normally holding 30 the sleeve in extended position against the stop.
3. In a tool of the character described, a shank having a bifurcated end, a bit mounted in the bifurcated end for swinging movement to permit reversal thereof, a freely rotatable sleeve slidable on the shank for movement over the bifurcated end to hold the bit in its reversed position, a pivot screw for detachably holding the bit in said bifurcated end and forming a stop for the sleeve, a stock rotatably supporting the shank, a ferrule on said stock and surrounding the shank and sleeve, and means within 45 the ferrule and acting upon the sleeve to normally hold the same extended against the stop.
- 50 4. The combination with a stock, a shank

rotatably mounted in and projecting from said stock, a ferrule on said stock surrounding the shank, a freely rotatable sleeve slidable on the shank and fitting at its inner end within the ferrule, a spring coiled on the shank and engaging the sleeve and arranged within the ferrule, means for limiting the longitudinal movement of the sleeve, and a 60 double-ended bit pivoted on the outer end of the shank and adapted to be reversed, said sleeve retaining the bit in either of its adjusted positions.

5. In combination with a stock, a shank 65 rotatably mounted in and projecting from said stock, a ferrule on said stock surrounding the shank, a freely rotatable sleeve slidable on the shank and fitting at its inner end within the ferrule, said sleeve having 70 at its outer end a knurled external surface, a spring coiled on the shank and gaging the sleeve and arranged within the ferrule, means for limiting the longitudinal movement of the sleeve, and a double-ended bit pivoted on the outer end of the shank and adapted to be reversed, said sleeve retaining the bit in either of its adjusted positions, and said knurled external surface being adapted to be grasped when 75 rotating the shank within the sleeve.

6. In a tool of the character described, a stock having a hand grip and also provided with a socket, a shank rotatable in the socket, a pawl-and-ratchet mechanism for 85 said shank fitted in the socket, a ferrule surrounding the shank and fitted on the stock and inclosing said pawl-and-ratchet mechanism, a manually movable actuator cam rotatable on the shank and engageable with 90 the pawl of said pawl-and-ratchet mechanism for moving the same, a sleeve rotatably supported upon the shank and fitted for sliding movement within the ferrule, and a coiled expansion spring surrounding 95 the shank within the ferrule and bearing at one end against the sleeve to normally hold the latter extended and at the other end bearing against the actuator cam.

In testimony that I claim the foregoing 100 as my own, I have hereto affixed my signature.

EDWARD H. BARTON.
